UNITED STATES PATENT OFFICE

WALTER BENNHOLD, OF FURSTENWALDE, GERMANY

APPARATUS FOR PRODUCING WATER GAS

Application filed October 23, 1928, Serial No. 314,367, and in Germany October 26, 1927.

This invention relates to a water-gas generator with drying and distilling apparatus for pulverulent coal, and more particularly to a generator for the distillation of fine grain or pulverulent fuels in continuous operation.

The pulverulent fuel is injected by means of a downwardly directed nozzle into a perpendicularly disposed water gas generating chamber, which is traversed unidirectionally by a previously highly heated current of water gas. At the same time steam is admitted, so that in the water gas generating chamber conversion into water gas takes place immediately. Regeneration is effected in a two-chamber heater arranged centrally about the water gas generating chamber, the said heater having two chambers or compartments. One chamber supplies heat to the water gas entering together with the steam at the bottom, and in the other chamber a part of this gas is burnt together with air, while continuously pre-heated water gas flows into the water gas generating chamber in a downward direction. The water gas generating chamber communicates at its lower end with a separating chamber for deposit and removal of the ash, the circulatory current of gas and the fresh gas generated also being passed from this widened portion to a scrubber. The waste gases are expelled from the particular regenerator chamber which is heated through a socket situated at the bottom.

If pulverulent coal is employed, which previously requires subjection to a distilling or even drying operation, the invention may be extended so as to combine the apparatus described above with an apparatus for the purpose in question, whereby circulatory gas is likewise employed for conveying both the fuel as well as the heat. A particularly favorable arrangement is in this manner obtained by reason of the fact that the sensitive heat of the current of gas may then be utilized, this heat, as shown by experience and actual practice, being quite sufficient for conducting a drying and distilling operation, even in the case of fuel containing a large percentage of moisture. By employing the water gas as a vehicle

it is moreover possible to obtain a simple closure of all transport connections perfectly safe against explosion. Finally, the steam released upon the drying operation may, as in the case of other known processes, be employed for generating the water gas, and introduced into the reaction zone through the medium of the circulatory current.

By way of example a form of embodiment of an apparatus will now be described suitable for drying, distilling and gas-generating purposes when employing moist or pulverulent raw brown coal. In this connection it is also possible to employ the coal in somewhat coarser form, i. e., in small lumps, if necessary previously reduced to the desired size, as the same has the tendency when entering the hot current of gas to crumble or break up into minute pieces which are readily picked up by the gas and carried along with the same.

The drawing illustrates in elevation the apparatus in question in diagrammatical form.

Referring now to the drawing, 15 is the water gas generator together with the regenerator chambers 15^a and 15^b. The air and steam admissions 15^c and 15^d, respectively, are shown diagrammatically in the drawing. From the reaction chamber the water gas passes into the separating chamber 16, from which latter the ash may be removed at the bottom through any suitable outlet 16^a. The water gas upon its exit has a temperature of approximately 700° F., and flows to a second dust or ash separator 17, which is roughly of a combined cylindrical and conical form. From 17 the gas is conveyed through two parallelly disposed and somewhat inclined pipes 18 and 19. In the pipe 18 raw coal is introduced through a pipe 18^a shortly behind 17. The coal is conveyed to the point of introduction from a bunker 20 via an intermediate bunker 21 through the medium of any known suitable means, not shown, which will effect the passage from bunker to intermediate bunker in such manner that a gastight closure is maintained.

The raw coal picked up and carried along by the hot current of water gas is dried down

to a moisture content suitable for the ensuing part of the process. The drying pipe 18 must accordingly be of a suitable length, while the speed of the gas may be taken at approximately 30 metres per second. The dried coal then falls into a bunker 23. A part of the current of gas passes out at the lower end of the same, and conveys at a high speed in a narrow pipe 24 the predried coal back to an intermediate bunker 25 above the pipe 19. If desired, the pipe 24 and the pipe 30, which latter communicates with the upper end of the bunker 23, may be provided with valves to regulate the flow of water gas through these pipes. As the manner in which the pipes 24 and 30 may be equipped with valves is clearly apparent to any one skilled in the art, and as the apparatus is diagrammatically illustrated, it is believed that it is not necessary to show these valves in the drawing. From this bunker the coal by means of a device similar to that described in connection with the parts 20—21 is introduced into the pipe 19, which is likewise traversed by hot water gas and in which, at approximately the same velocity as in 18, the final drying and distilling operation is performed. The coal in partly coked condition passes into a bunker 26, and if necessary from the latter into an adjacent disintegrating apparatus 27. In the form of powder the semi-coke is now conveyed through the pipe 28, likewise through the medium of water gas under pressure, into the bunker 29, from where it is conducted at high speed to the reaction chamber 1 of the water gas generator.

For the conveying lines 24 and 28 it is accordingly possible on each occasion to employ a branched-off current of the circulating water gas. The remainder of the main quantity of gas passing out through the bunkers 23 and 26 is conveyed through pipes 30 and 31 to a cooling apparatus 32 and, if necessary, to a tar separating apparatus 33. A part of the gas is branched off and, taken through a separate scrubber 34, withdrawn in the form of useful gas. The remainder is cooled in a special fine-cooling apparatus 35 down to a desired steam content, and returned through the pipe 36 back into the gas generator.

The whole arrangement accordingly forms a circulatory system of water gas, from which, beyond the useful gas, merely the gas passing out of the intermediate container 25 and the bunker 29 is branched off. This conveying gas, to enable the same to be additionally employed, would require to have the dust separated therefrom; this, however, does not present any great difficulty.

In the drawing the blowers employed for placing the gas under pressure have not been shown, as the same may be mounted in any suitable manner in accordance with particular requirements.

It will be understood that no restriction is made to the exact embodiment shown which, as will be appreciated, is merely intended diagrammatically, and that various modifications may be made without departing from the spirit of the invention. 70

What I claim as new and desire to secure by Letters Patent is:

An apparatus for generating water gas, having in combination; a water gas generating chamber, regenerators adjacent the chamber, means for admitting air and steam to the chamber, means for admitting finely divided fuel to the chamber, a primary dust and ash separator beneath and connected to the water gas generating chamber, a second separator connected to the primary separator, two parallel inclined pipes for conveying water gas and drying finely divided fuel connected to the second separator, means for introducing finely divided fuel to each of said pipes and means for conveying the dried fuel into said first-named fuel admission means. 85

In testimony whereof I have affixed my signature. 90
